ROAD SANDING APPARATUS

Arthur C. Hopkins, Tupper Lake, N. Y., assignor
to Artomatic Machinery Corp., Tupper Lake,
N. Y., a corporation of New York

Application May 23, 1941, Serial No. 394,862

3 Claims. (Cl. 275—2)

This invention pertains to a road sanding apparatus which may be mounted upon a standard motor truck chassis of suitable size, preferably one having a conventional auxiliary power take-off mechanism.

An object of this invention is to provide a road sanding apparatus comprising a hopper having an open bottom provided with an improved discharging mechanism capable of delivering sanding material from the hopper to a spreading mechanism at a rate automatically varying in accordance with the speed of travel of the truck on which the sanding apparatus is mounted, said discharging mechanism including an endless conveyor positioned immediately beneath the open bottom of the hopper and serving substantially to close the same and to support the material contained in said hopper.

A more specific object of the invention is to provide an improved conveyor mechanism which is simple and durable in construction and is positive and economical in operation.

Yet another object of the invention is to provide a suitable drive mechanism associated with the drive shaft and power take-off mechanism of the truck for actuating the conveyor in either a forward or a rearward direction, the operation of the conveyor in the forward direction being from the drive shaft and serving to deliver the sanding material to a spreader at a rate in proportion to the speed of operation of the truck, the operation of the conveyor in the rearward direction being from the power take-off mechanism and serving to deliver the sanding material in a compact stream at the rear of the truck independent of the movement of the truck.

A still further object of the invention is to provide simple and efficient mechanical means functioning independently of the speed of operation of the truck and conveyor for receiving the material discharged from the conveyor and distributing the same evenly upon the road bed.

These and other objects and advantages pertaining to the specific construction of the apparatus and to the form and relation of the parts thereof will more fully appear from the following description taken in conjunction with the accompanying drawings in which:

Figure 1 is a side elevation of a motor truck having a sanding apparatus embodying the various features of this invention operatively mounted thereon.

Figure 2 is an enlarged transverse sectional view taken substantially on line 2—2, Figure 1, portions of the hopper being broken away.

Figure 3 is a detail vertical sectional view taken substantially on line 3—3, Figure 2, intermediate portions of the hopper and conveyor being broken away.

Figure 4 is a detail horizontal sectional view showing my improved spreader mechanism and the drive mechanism for operating the conveyor.

Figure 5 is an enlarged detail horizontal sectional view taken substantially in the plane of line 5—5, Figure 3, showing a section of my novel conveyor.

Figure 6 is a detail transverse sectional view taken on line 6—6, Figure 5.

Figure 7 is a detail longitudinally sectional view taken substantially on line 7—7, Figure 5.

The sanding apparatus, as illustrated in the drawings, comprises primarily a hopper 10, a spreader 11 and a conveyor 12 for transferring the material contained in the hopper 10 to the spreader 11.

The hopper 10 has downwardly and inwardly inclined side walls 14, a downwardly and rearwardly inclined front end wall 15 and a vertically disposed rear end wall 16. The sides 14 are secured at their lower edges, as by angle bars 17, to a base or frame 18. The base 18 comprises side channel bars 19 arranged in an upright position, connected at their forward ends by an end plate 20, and supported upon and secured to cross bars 21. These cross bars 21 rest upon and extend transversely of the truck chassis or frame from one sill 22 to the other sill 22 of the truck chassis, to which sills they are suitably secured. The hopper 10 is provided with inwardly extending deflector blades 23 arranged longitudinally of the hopper at the upper sides of the base 18 adjacent the side bars 19. These deflector blades may be secured to the hopper and base 18 in any suitable manner, as by the angle bars 17 as shown in Figure 2.

The conveyor 12 is mounted within the base 18, as shown in Figures 2 and 3, beneath the deflector blades 23. This conveyor comprises a pair of endless link-belts 25, each of which travels over a pair of sprocket wheels 26 and 27 mounted upon corresponding shafts 28 and 29. The shafts 28 and 29 extend transversely through the base 18 and are journaled in the side members 19. The shaft 29 is mounted in the base 18 adjacent the rear end of the hopper 10, while the shaft 28 is positioned at the forward end of the base in advance of the forward end 15 of the hopper. One end of shaft 28 extends outwardly beyond the adjacent side member 19 and has secured thereto a worm gear 31 which has meshing engagement

with a worm 32 mounted on a short shaft 33. The shaft 33 is journaled in suitable bearings 34 mounted on the base 18 and, as shown more particularly in Figure 4, is connected by means of universal joints 35 and an intermediate shaft 36 to a drive shaft 37 journaled in suitable bearings 38 secured in any suitable manner to the chassis sill 22 adjacent thereto. The shaft 37 is operatively connected by a pair of beveled gears 40 with the drive shaft 41 of a power take-off unit 42 connected with the transmission gearing of the truck drive mechanism contained in the usual manner in a case indicated at 43.

It will be understood that the power take-off mechanism and the connection thereof with the transmission gearing of the truck may be of any suitable construction, and as usual, the power take-off is provided with an operating lever 45 which may extend upward into the cab C of the truck whereby the operation of the power take-off mechanism may be manually controlled.

The link-belts 25 of the conveyor 12 are of conventional construction, comprising side bars 47 and 48 connected by pins 49. Mounted on each pin 49 between the links 47 and 48 is a roller 50. In order that the link-belts will not sag intermediate the sprockets 26 and 27 there are provided two sets of track members 52 and 53. One set of the track members, as 52, is secured to the adjacent side bars 19 of the base 18 in position to be engaged by the rollers 50 at the upper run of the belt. The other set of track members 53 is secured to the cross bars 21 of the base 18, as indicated in Figure 2, for supporting the lower run of the link-belts.

The link side bars 48 positioned at the inner sides of the link-belts are provided with laterally disposed attachment lugs 48' to which are secured attachment arms 55 as by rivets 56. The attachment arms 55 of corresponding opposed links 48 of the link-belts are secured as by electric welding to corresponding ends of trough-like bars 57 disposed transversely between the link-belts. These bars 57 are V-shaped in cross section and are so constructed and secured to the attachment arms 55 that the longitudinal edges of each bar substantially coincide with the lines connecting the axes of the pins 49 of the opposed adjoining links, as shown more particularly in Figure 7. It will be observed, by referring to Figure 7, that by arranging the cross bars 57 of the conveyor in this manner, the longitudinal edges of the bars travel on the pitch circle of the sprockets 26 and 27 as the bars pass from one run of the belt to the other. This maintains the adjacent bars in contact with each other as they pass around the sprocket wheels and prevents a separation of the bars from each other, as would be the case if the longitudinal edges of the bars were located at any position other than at the axes of the corresponding pins 49. The longitudinal edges of the cross bars of the conveyor are thus always maintained in contact with each other and escape of sanding material from the conveyor before said material has been moved to the end of the conveyor is prevented.

As hereinbefore stated, the conveyor may be operated from the power take-off mechanism 42, and when so operated the upper run thereof is driven rearwardly so that material carried thereby from the hopper 10 will be discharged from the conveyor at the rear of the truck. The base 18 may be provided with a chute 59 secured to the rear cross bar 21 thereof in any suitable manner to extend laterally of the truck for receiving

the material discharged from the rear end of the conveyor and guiding the same to one side of the truck.

A main drive mechanism 60, as shown more particularly in Figure 4 of the drawings, is provided for operating the conveyor in the forward direction. This main drive mechanism 60 comprises a pulley 61 mounted on the drive or propeller shaft 62 of the truck to be rotated thereby. Pulley 61 is operatively connected by a series of, in this instance three, belts 63 with a loose pulley 64 rotatably mounted upon the shaft 37. The pulley 64 is provided at one end with a clutch element 65 which is adapted to be engaged by a companion clutch element 66 splined in any suitable manner to the shaft 37 to be rotated by said shaft and for axial movement with respect thereto. The clutch element 66 may be moved longitudinally of the shaft 37 into and out of engagement with the clutch element 65 in any suitable manner as by a lever indicated at 67. This lever 67 may be pivoted as at 68 to the chassis of the truck whereby the clutch element 66 may be manually operated for operatively connecting the conveyor drive shaft 37 with the drive shaft 62 of the truck. It will be observed that when these shafts 37 and 62 are thus connected with each other, by the main drive mechanism 60, the conveyor will be operated only when the drive shaft 62 is in operation and that the speed of operation of the shaft 37 and therefore of the conveyor 12 will be in proportion to the speed of operation of the drive shaft 62.

A chute 70 is mounted beneath the base 18 and intermediate the front and rear wheels W and W' of the truck for receiving the material discharged from the forward end of the conveyor 12. The chute 70 as shown in Figures 2 and 3, is connected to an adjacent cross bar 21 and the end plate 20 of the base 18. This chute is provided with a pair of forwardly projecting spouts 71 which extend downwardly at opposite sides of the truck drive shaft section 62'.

Beneath the chute 70 is mounted the hereinbefore mentioned spreader 11. This spreader 11 comprises a shaft 73 which extends transversely of the truck chassis beneath the sills 22 and is journaled in suitable brackets 74 secured to said sills. Shaft 73 has secured thereto a pair of spreader members 75 and 76. Each of these spreader members comprises a hub portion 77 which is secured to the shaft 73 in alignment with a corresponding spout 71. Connected with each hub portion 77 is a spiral blade 78 which has the inner end portion 78' thereof bent to extend in a general direction axially of the hub 77. The shaft 73 and blades 78 are rotated in a counter-clockwise direction as viewed in Figure 1, from the left-hand side of the truck.

Any suitable means may be provided for rotating the shaft 73 independently of the speed of operation of the truck, such as a small gas engine 80 mounted on a bracket 81 secured to the truck chassis. The motor 80, as shown in Figure 2, is operatively connected with the shaft 73 by a belt 82 trained over pulleys 83 and 84 secured to the drive shaft 85 of the motor and shaft 73 respectively. It will be observed that, due to the particular construction of the spreader blades 78 and the arrangement thereof with respect to the spouts 71, material passing from the conveyor 12 through the chute 70 will flow over the shaft 73 and be engaged by the spreader blades 78. The blades 78, owing to their direction of rotation, tend to throw the sanding material both for-

wardly and laterally with respect to said truck. The distance the material is thrown laterally with respect to the truck depends upon the speed of rotation of the spreader. It will now be observed that, in as much as the speed of rotation of the spreader is controlled independently of the speed of operation of the truck, the lateral disposition of the material may be very effectively controlled irrespective of the speed of operation of the truck or the quantity of the material passing through the chute 70. The inner end portion 78' of each blade, as indicated more particularly in Figure 2 of the drawings, is of arcuate formation, the curve of which is the reverse of the general line of curvature of the outer portion of the blade so that material contacting the blade portion 78' is dispensed toward the central vertical plane of the truck and thereby produces a substantially even distribution of the material transversely of the road bed within predetermined limits.

As shown more particularly in Figures 2 and 3 of the drawings, the forward end wall 15 of the hopper 10 is provided along its lower edge with an outlet opening 87 communicating with a discharge chamber 88 formed at the forward end of the hopper 10 by vertically disposed side plates 89 secured to the hopper and base 18 at opposite sides of the opening 87 and an end wall 90. The wall 90, in this instance, is pivotally connected to the side plates 89 by a shaft 91 secured to the upper edge of the wall 90 and journaled in the plates 89. The lower end of the member 90 terminates adjacent the upper run of the conveyor 12 and is yieldingly maintained against outward or forward swinging movement by means of a pair of coil springs 93 arranged at opposite sides of the hopper 10. The rear ends of the springs are connected with the hopper, while the forward ends thereof are connected to corresponding arms 94 secured to the outer ends of the shaft 91. The inwardly or rearwardly swinging movement of the member 90 is limited by one or more adjustable stops 96. Each stop 96 may be in the form of a bolt having screw thread engagement with a support or bracket 97 secured to the hopper 10, and arranged in the path of movement of one of the arms 94 for contact therewith.

In order manually to adjust the member 90, with respect to the conveyor 12, for maintaining the lower end of said member 90 in a desired spaced relation to the conveyor and thereby govern the quantity of material conveyed from the discharge chamber by the conveyor, I have provided a cable 99 having one end attached to the member 90. This cable extends forwardly from member 90 over a sheave 100 connected by a bracket 101 to the forward end of the base 18, and then under a second sheave 102 secured to the chassis of the truck beneath the cab C, the forward end of the cable being connected with the lower end of a lever 103 which extends upwardly through the floor of the cab in convenient position to be actuated by a person within the cab. The lever 103 may be provided with a latch and tooth segment structure 104 by which the lever may be releasably maintained in any one of a plurality of predetermined positions. It will now be observed that the member 90 functions as a gate to govern the amount of material carried by the conveyor as it leaves the discharge chamber 88 and at the same time will yield under excessive pressure as when relatively large rocks or other solid objects are being conveyed along the conveyor to allow such objects to pass from

the discharge chamber without injury to the mechanism. These rocks or other objects will, of course, be deposited in the chute 70 and pass downwardly and out of the forward ends thereof and are usually urged to the side of the road by the spreader.

It will now be observed that when the hopper 10 contains a suitable sanding material such as sand, cinders, or the like, this material may be discharged from beneath the hopper at either the forward or the rear end thereof depending upon the direction of movement of the conveyor 12. It is very often desirable to deposit sand, cinders, or the like adapted for use in sanding and repairing roads in relatively small piles adjacent the side of the road. It is also frequently desirable, after completing the sanding of an icy road, to remove any unused sanding material from the hopper 10, in order to prevent freezing of the sanding material in the hopper, particularly if the truck is to stand for a considerable period in an unheated place. In such cases, the main drive mechanism 60 is first rendered inoperative by movement of clutch element 66 out of engagement with the clutch element 65, the power take-off mechanism 42 is connected to be driven by the truck motor by means of its operating lever 45, and the conveyor 12 is then driven in the rearward direction. Material carried rearwardly by the conveyor passes beneath the lower edge of the rear wall 16 of the hopper and is deposited in the chute 59. The lower edge of the rear wall 16 is arranged in predetermined spaced relation to the upper run of the conveyor 12, for this purpose. However, it will be observed that other means such as a gate construction somewhat similar to the gate 90 may be readily used in conjunction with the conveyor for governing the passage of material from the rear end of the hopper 10.

When it is desired to use the apparatus for spreading material contained in the hopper 10 upon the road surface, the power take-off mechanism 42 is rendered inoperative and the main drive mechanism 60 is rendered operative by engagement of the clutch elements 65 and 66. Furthermore, the spreader 11 is caused to be operated by the motor 80, while the gate 90 is adjusted by means of stop element 96 to permit only a predetermined minimum quantity of material to pass along the conveyor beneath said gate. The more vertical the position of the gate and the closer the edge thereof is maintained to the conveyor, the thinner is the layer of the material carried by the conveyor from the discharge chamber 88. The truck is now set into operation and the speed of movement of the conveyor will, of course, be in proportion to the speed of the truck. It is desirable that the material spread upon the road surface be confined in a strip not much wider than the distance between the outer sides of the rear wheels W' of the truck. This width of the layer of sanding material is readily controlled by the speed of operation of the spreader 11, which in turn is governed by the speed of operation of the motor 80. It is sometimes desirable to add more of the sanding material to some portions of the roadway than to other portions thereof and a man in the cab may readily govern the amount of material applied to the roadway without stopping the operation of the truck by merely manipulating the lever 103 to adjust the gate 90 with respect to the conveyor 12. It will thus be understood that I have produced simple, efficient means whereby

road sanding material may be quickly and economically applied to roadways and in such a manner as to enable the truck to operate most efficiently due to the sanding material being discharged upon the roadway in front of the rear drive wheels of the truck. This is particularly advantageous when passing around icy curves and along steep grades.

Although I have shown and particularly described the preferred embodiment of my invention, I do not wish to be limited to the exact construction shown, as various changes both in the form and relation of the parts thereof may be readily made without departing from the spirit of the invention as set forth in the appended claims.

I claim:

1. An apparatus for sanding roads or the like adapted to be mounted upon a motor truck and comprising in combination, a hopper having an open bottom, an endless conveyor extending forward and rearward of the truck and located immediately beneath said open bottom and so constructed and arranged as to have an upper run serving to substantially close said open bottom and to support material contained in said hopper against gravitational discharge through said open bottom, said hopper having a forward outlet disposed transversely of and immediately above said upper run of the conveyor and adapted to permit discharge of material therethrough and over the forward end of the conveyor upon travel of the upper run of the conveyor in the forward direction, a spreader for receiving and laterally distributing material discharged through said outlet, said spreader being constructed to deposit material in advance of the rear wheels of the truck, manually controlled means for driving said conveyor in said forward direction at a speed dependent upon the forward speed of the truck, whereby material may be spread at a rate automatically varying in accordance with the forward speed of the truck, said hopper having a rear outlet disposed transversely of and immediately above said upper run of the conveyor and adapted to permit discharge

of material therethrough and over the rear end of the conveyor upon travel of the upper run of the conveyor in the rearward direction, and manually controlled means for driving said conveyor in said rearward direction regardless of the movement of the truck, whereby material may be discharged at the rear of the truck whether the truck is moving or standing.

2. The combination as claimed in claim 1 in which said conveyor comprises a pair of spaced link-belt chains cross connected by bars the edges of which substantially coincide with the axes of the pins of the chains.

3. An apparatus of the character described adapted to be mounted upon a motor truck and comprising in combination, a hopper having an open bottom, an endless conveyor extending forward and rearward of the truck and located immediately beneath said open bottom and so constructed and arranged as to have an upper run serving to substantially close said open bottom and to support material contained in said hopper against gravitational discharge through said open bottom, said hopper having forward and rear outlets disposed transversely of and immediately above said upper run of the conveyor and adapted to permit discharge of material therethrough and over the forward or rear end of the conveyor respectively upon travel of the upper run of the conveyor in the forward or rearward directions respectively, a spreader for receiving and laterally distributing material discharged through the forward outlet, said spreader being constructed to deposit material in advance of the rear wheels of the truck, and manually controlled means for selectively driving said conveyor from the truck motor either in said forward direction in proportion to the forward speed of the truck or in said rearward direction regardless of the movement of the truck, whereby material may be either spread in advance of the rear wheels of the truck or deposited in a compact stream at the rear of the truck.

ARTHUR C. HOPKINS.
